UNITED STATES PATENT OFFICE.

JOHN C. WAHL, OF CHICAGO, ILLINOIS, ASSIGNOR TO WAHL ADDING MACHINE COMPANY, A CORPORATION OF ILLINOIS.

CALCULATING-MACHINE.

No. 893,719.

Specification of Letters Patent.

Patented July 21, 1908.

Application filed October 23, 1905. Serial No. 283,887.

To all whom it may concern:

Be it known that I, JOHN C. WAHL, citizen of the United States, residing at Chicago, in the county of Cook and State of Illinois, have 5 invented a certain new and useful Improvement in Calculating-Machines, of which the following is a full, clear, concise, and exact description, reference being had to the accompanying drawings, forming a part of this 10 specification.

My invention relates to calculating machines or devices, and more particularly to compact calculating mechanism adapted for separable attachment to typewriting machines for automatically performing calculations.

My device is of the same class as that described in my co-pending application Serial No. 256,141 filed April 17, 1905, and the object is to provide more simplified and improved construction and arrangement of the various operative parts and to provide more efficient and simplified adjusting, checking and correcting means. A device of this kind 25 is more particularly adapted for calculations of addition and subtraction, and may be directly associated with the number keys of any style of typewriting machine and with the escapement mechanism thereof, and upon 30 actuation of the number keys of the machine the corresponding numbers will be printed upon the sheet and simultaneously registered on indicating mechanism. At the end of a calculation the desired result will appear 35 on the indicating mechanism and may be copied therefrom and printed on the sheet.

The indicating mechanism is in the form of a totalizer adapted for suitable mechanical association to travel with the escapement 40 carriage, while the driving mechanism for the indicating mechanism is fixed to the typewriter frame and its various operative parts are suitably associated with the number keys of the machine. There are also several auxiliary 45 controlling, adjusting, checking and correcting mechanisms associated with both the indicating and the driving mechanisms. These auxiliary mechanisms perform very important functions. One of said mechanisms serves upon actuation of the key to correct for any lost motion or relative displacement of the machine parts and to set these parts so that upon actuation of any key there will be proper alinement and the calculating 50 parts and printing parts in the proper posi-

tion for performing their functions. This same mechanism also prevents escapement or slipping of the carriage until the calculation and printing has been completed.

It happens very often in the operation of machines of this kind that a key is not moved to the end of its stroke, or that two or more keys are struck at the same time. This, of course, unless corrected for will introduce errors into the calculations, and the purpose 60 of another of the auxiliary mechanisms is to cause restoration of wrongfully or accidentally actuated parts and to restore calculating mechanism parts to withdraw therefrom the wrong or undesired calculation. Other undesirable actuations or displacements of the operative parts as those, for instance, due to momentum of the parts or to lost motion, are prevented by these auxiliary mechanisms. In general, it may be stated that all 65 operative parts are securely locked against displacement until the particular function intended for them is to be performed, this 70 insuring great reliability and efficiency.

The exact operation and detailed construction of the various main mechanism parts and of the auxiliary mechanism parts will be best understood by reference to the accompanying drawings which show my device attached to the well known Remington typewriting machine, and in which drawings,

Figure 1 is a side elevation of a typewriting machine showing the calculating mechanism attachment associated therewith. Fig. 2 is a front view of the typewriting machine with attached calculating mechanism. Fig. 3 is a detached view of the calculating mechanism and actuating or driving mechanism therefor, parts being shown in section and parts being broken away for clearness. Fig. 4 is a view similar to Fig. 3, showing the apparatus in a different operative position. Fig. 5 is a front view of the parts shown in Figs. 3 and 4. Fig. 6 is a detached plan view of the main driving gear of the driving 90 mechanism and adjusting mechanism therefor. Fig. 7 is a view similar to Fig. 5, showing auxiliary controlling and adjusting mechanisms, parts being broken away. Fig. 8 is a detached sectional view taken on line 8—8 of Fig. 7. Fig. 9 is a detached sectional view taken on line 9—9 of Fig. 7. Fig. 10 is a detached sectional view taken on line 10—10 of Fig. 7. Fig. 11 is a detached plan view of the totalizer frame showing the 100 105 110

arrangement of the totalizer mechanisms. Fig. 12 is a detached enlarged view showing 5 detent lever mechanism for locking the first gear of the totalizer mechanism. Fig. 13 is a detached view showing locking mechanism 10 for engaging the indicating mechanism with the escapement carriage. Fig. 14 is a sectional view on a diametrical plane through the locking mechanism in Fig. 13 to show the connection of this locking mechanism 15 with the indicating mechanism supporting frame. Fig. 15 is a detached view of the adjusting rack for tabulating mechanism. Fig. 16 is a view showing a modified arrangement 20 of the totalizer gear wheels within their supporting frame. Fig. 17 is a view of some of the parts shown in Fig. 10 while those parts are in one position and Fig. 18 is a view of the same parts while in another 25 position. Figs. 19, 20 and 21 are views of some of the pieces shown in Figs. 17 and 18, to more clearly illustrate the same.

The device although shown as attached to a Remington typewriting machine may be 30 adapted to be attached to other machines with equal facility.

A horizontal track bar 1 is secured to hangers 2—2 fastened to the frame 3 of the typewriting machine by means of screws 4—4 as 35 best shown in Fig. 2. This track bar or frame has an upper and a lower raceway or track 5 and 6 respectively adapted to be engaged by upper and lower rollers 7 and 8 pivoted from shafts 9 and 9' extending from the 40 back of the totalizer supporting frame 10. This totalizer frame is thus adapted for longitudinal travel along the track frame 1, and the arm 11 connects with this frame and with the bar or arm 12 secured to the rear 45 non shiftable, or comparatively stationary part 13 of the typewriter carriage by means of the screws 14. This arm 12 is disposed at the side of the machine in such manner as to clear the front shiftable or relatively movable part 15 of the escapement carriage supporting the type roller 16, this frame, as is well known, being adapted to be swung about the stationary frame 13 so that printing on the sheet held on the roller can be examined 50 during the operation of the machine, and it is therefore unnecessary to disconnect the indicating mechanism each time that the front part 15 is raised, this being a very important feature, as otherwise there might be disarrangement or displacement of the indicating mechanism parts which would result in errors. The arm 12 is, however, adapted for separable engagement with the arm 11 so that the typewriting machine can be used in 55 its ordinary capacity entirely independently of the calculating mechanism. At the end of the arm 11 a head 16' is provided having a tongue or extension 17 for engagement in the slot 18 through the front end of the arm 12.

60 To connect the indicating mechanism with the

escapement carriage the head 16' is turned to carry the arm 17 within this slot, and to disconnect the indicating mechanism the head 16' is turned to disengage the tongue. Care must also be taken to connect the totalizer supporting frame in proper relation with the escapement mechanism of the carriage, and the head 16' is therefore pivoted on the sleeve 18' having adjustable threaded engagement with the end of the arm 11. A lock nut 19 secures the sleeve in any adjusted position and the screw 20 holds the head on the sleeve. The totalizer supporting frame 10 will follow all the movements of the escapement carriage, and to cause the frame 10 to move in a straight longitudinal line without displacement or lost motion the tracks 5 and 6 on the track bar 1 are preferably as shown, the center parts thereof being the prismatic ridges 21 and 22 respectively, 85 having at each side thereof the horizontal track ways 23 and 24 respectively. The rollers 7 and 8 to correspond have the shape of a spool, the cylindrical center 25 of each spool bearing on the outer face 26 of the corresponding ridge, the angular faces 27 bearing 90 on the sides of the ridge part and the cylindrical edges 28 bearing on the horizontal surfaces 23. This form of track and engaging spool causes the supporting frame 10 to 95 be at all times perfectly rigid without increasing the friction.

The upper and lower edges of the supporting frame 10 are provided with V-shaped guideways or channels 29 and 30 respectively, 100 and a totalizer frame 31 has the side walls 32 and 33 provided at their rear ends with the upper and lower V-shaped tongues 34 and 35 for engaging in the guideways 29 and 30, within which guideways the totalizer frame 105 may be slid, and to secure the totalizer in any adjusted position on the supporting frame 10 a locking lever 36 may be suitably pivoted to the totalizer frame so that its end 37 may be brought into engagement in any 110 of the slots 38 along the top front edge of the traveling frame 10. These slots are scaled to correspond to the spacing distances of the typewriting machine so that the starting point of the totalizer may agree with that 115 of the typewriting machine. The totalizer frame when thus adjusted in position on the traveling frame 10 will travel back and forth across the front of the machine with the escapement carriage, and the indicating and calculating mechanisms contained by the totalizer frame will be described later.

Depending from the track bar are arms 39 and 40 terminating respectively in side plates 41 and 42, the arms being connected by a 125 horizontal supporting plate 43, and near the center of this supporting plate 43 is mounted the driving frame 44, consisting of the side plates 45 and 46 which may be secured to the supporting plate by the screws 47. Pivoted 130

in the top forward end of the side plates is a shaft 48 supporting the gear wheel 49, which I shall call the actuating gear and which is adapted to engage with gear wheels of the indicating mechanism or totalizer which travels across the machine. This gear wheel is rigidly secured to the sleeve 50 which is secured to the shaft 48. To the left of the gear wheel 49 is the controlling gear 52 which is rigidly secured to the sleeve 51 slidably but non rotatably mounted upon the shaft 48. The two gears 49 and 52 thus always turn together but gear 52 is smaller in diameter than gear 49 so as not to interfere with the totalizer as the latter travels past it. To the left of this controlling gear in said sleeve is the groove 53. To the rear of the shaft 48 and parallel thereto is a second shaft 54 journaled in the wall 46 and the wall or plate 55, this shaft being adapted for longitudinal movement. As best shown in Fig. 6 two gear wheels 56 and 57 are rigidly secured by means of a hub or sleeve 58. This sleeve and the connected gear wheels are loose upon shaft 54 so as to rotate thereon. Gear 57 is always in mesh with the gear 52. To the left of gear 57 a collar 59 encircles the shaft 54, and has an arm 60 extending therefrom with a bifurcated end 61 entering the groove 53 in the sleeve 51.

A controlling lever 62 is secured to the end of the shaft 54 and terminates in a finger piece 63, the lever 62 being held in its extreme positions of adjustment in the slots 64 and 65 cut in the plate 66 which is secured to the wall 46. A spring 67 tends to draw the lever 62 toward the plate 66.

As will be more fully described later, a segmental driving gear 68 is adapted upon actuation of keys of the machine to be moved to the dotted position shown in Fig. 5 and then rotated. In the positions shown in Figs. 5 and 6 this segmental gear will be moved into mesh with the gear 56 and rotation of this segmental gear will be transmitted through the gear 57 and controlling gear 52 to the actuating gear 49 to cause rotation in one direction of the indicating mechanism gear wheels engaged thereby. Upon moving the lever arm 62 to the other end of the plate 66 the shaft 54 with the sleeves and gears thereon will be moved longitudinally toward the right. While the bifurcated end of the arm 60 travels across the slot 53 there will be no movement of the gear 52, but when the end of the slot is reached the gear 52 will also move to the right and the gear 56 will have been moved to the right beyond the teeth of the segmental gear 68, but the gear 52 will have been moved so that upon actuation of the segmental gear its teeth will be brought into mesh with this gear 52 only, and upon subsequent rotation of the segmental gear the actuating gear 49 will be moved in an opposite direction. In other words, in the

position of the parts shown in Figs. 5 and 6 the gear 49 will be actuated through the reversing gears 56 and 57 to cause negative or subtracting movement of the indicating parts, while with the lever 62 at the right end of the plate 66 the segmental gear 58 will engage directly with the gear 52 to cause forward or adding movements of the indicating mechanism parts upon rotation of the gear 49. The gear 57 is at all times in mesh with the gear 52 but is ineffective during forward rotation of the gear 49.

Below the shafts 48 and 54 is pivoted a parallel shaft 69 between the end walls 41 and 42. The segmental gear 68 before referred to is in the form of a rim 70 and arm 71 having the slot 72 at its lower end spanning the shaft 69, and a pivot pin 73 passes through the arms 74 and 75 and through said shaft, whereby the segmental gear frame may swing laterally and when in a vertical plane to mesh with either the gear 56 or the gear 52 of the driving mechanism, as before described.

Between the shafts 48 and 54 and the shaft 69 is the shaft 76 secured in the walls 46 and 55. On this shaft is the sleeve 77 having the groove 78 in which engages the lower edge 79 of the rim 70 of the segmental gear frame. Directly below this shaft 76 is another shaft 80 to which a bell crank lever 81 is pivoted at its elbow 82, the end of the arm 83 of said bell crank lever being pivoted to the sleeve 77. The end of the other arm 84 of the bell crank lever is pivoted to the upper end of the link 85 having an elongated slot 86 at its lower end in which engages a pin 87 extending from the arm 88 extending from the shaft 89, which shaft is pivoted at its ends in the end walls 41 and 42. From the ends and from intermediary points of the shaft 89 extend supporting arms 90 carrying at their ends the universal shaft 91 on which is the roller 92.

Between the rear lower ends of the end plates 41 and 42 is pivoted a shaft 93, and in suitable position over each number key of the machine is a wing-shaped frame 94 connected at its one end to the corresponding machine number key by means of an adjustable turn buckle 95. Adjacent to each frame 94 is a cam arm 96 terminating in a cam surface 97. From an intermediary point between this cam surface and the shaft 93 is a post 98 engaging in the slot 99 through the adjacent frame 94. For each number key also there is an actuating lever 100 terminating in a cam roller 101 pivoted on the extension 102. Each cam roller is adapted for engagement with the cam surface 97 of the corresponding cam arm 96 so that upon depression of a key motion is transmitted from the frame 94 to the post 98, cam arm 96, and by means of engagement of the cam surface 97 with the cam roller 101 the corresponding lever 100 is swung to cause rotation of the 130

shaft 69 and a consequent rotation of the segmental gear frame 68. The several actuating levers 100 are angularly displaced corresponding to the amount of rotation required upon depression of a key. For instance, the actuating lever for key number 1 upon engagement with the cam arm 96 is rotated through an arc which will produce a rotation of the segmental gear frame 68 and 10 the driving mechanism driven thereby to cause the indicating mechanism to move one division, or, in other words, to move from one number to the next. The actuating lever for key number 9 will be displaced so 15 that upon engagement with the corresponding cam frame rotation will be produced of the segmental gear and of the driving mechanism to cause the engaged indicating mechanism to move the indicating wheel thereof 20 through 9 divisions. The intermediate actuating levers are displaced proportionally, the actuating cam arms, however, being all of the same length.

To cause more regular actuation of the 25 actuating arms and to prevent over actuation thereof due to the sudden impact with the cam arm upon striking of the number keys, the cam arm is in the form of a goose-neck, as best shown in Figs. 3 and 4, the end 30 of the arm being turned back to form the retaining wall 103 parallel to the cam surface 97, and the cam roller is confined in the cam slot. There is also an extension 104 from the bend of each goose-neck which in 35 the normal position of the keys engages against the plate 43 or vertical supporting walls 105 of the driving frame 46. There is also a projection 106 from the end of each goose-neck extending forwardly. This is for 40 the purpose of preventing simultaneous actuation of certain keys after other keys have been depressed. For instance, as shown in Fig. 4, where one key is shown depressed the cam roller on the lever arm 100' will be out- 45 side of the retaining projection 103 of the corresponding goose-neck, and if this goose-neck should be drawn down upon depression of the key the roller upon release of the keys will engage over the top of the goose-neck 50 and so block the machine. The roller, however, is struck by the underside of the projection 106 and another key cannot, therefore, be depressed when the first key is down.

Each wing frame 94 has a cam projection 55 107 from near the center of its periphery, and the cam face 107' and the edges 108 and 109 at the sides of the cam projection are preferably concentric with the shaft 93. Along the edge of the upper end of each wing frame, 60 which edge is concentric with the shaft 93, is a plurality of teeth 110 adapted for engagement with a locking tooth or web 111 pivoted between the end walls 41 and 42.

The distance between the pivot line and the 65 point of the locking web plus the distance of

the center line of the shaft 93 to the teeth 110 is slightly greater than the distance between the center line of the shaft 93 and the pivot line of the locking web. In the normal position of the keys as shown in Fig. 3 the 70 wing frames will be up and the teeth thereon will be back of the locking web. Upon depression of a key the wing frame will be rotated forwardly and the cam projection will lift the roller 93 on the shaft 92 into engagement with the cam surface 107', thus rotating the arms 90 and 88 secured to the shaft 89 and the upward movement of the end of arm 88 causes also upward movement of the link 85 and arm 84 of the bell crank 81, and 80 the arm 83 of the bell crank will be moved toward the left and also the sleeve 77 pivoted thereto, and the segmental gear frame engaging in the slot 78 will be swung to the left to a vertical position, as best shown in Fig. 5, 85 into meshing engagement with either the gear 56 or the controlling gear 52. The cam arm 96 upon depression of a key is not immediately positively actuated, but at the instant that a roller shaft engages the cam 90 surface 107' the end of the slot 99 will engage the post 98 extending from the shaft 96, and while the roller shaft rolls over the cam surface 107' to hold the segmental gear in meshing engagement the cam surface 97 95 becomes effective to cause the proper rotation of the corresponding actuating lever 100 and the shaft 69 to cause the engaged indicating mechanism number wheel to be rotated a distance corresponding to the number key depressed.

After the cam roller on the actuating lever reaches the cam surface concentric with the shaft 93 there will be no further rotation of the segmental gear and the roller shaft 105 leaves the cam surface 107' and is restored by gravity to its normal position to rest against the surface 109 of the wing frame 94. The link and bell crank lever mechanism is also returned to its normal position as by 110 a spring 113 and the segmental gear returned to its normal position out of mesh with the driving gear, this normal position being shown in Fig. 3. Upon depression of the key, also, the teeth 110 are carried by the 115 point of the locking web 111, this web being held in engagement with the teeth by the springs 114. The position of the teeth should be such that the locking point will be in engagement with teeth an instant before 120 the shaft roller 92 comes into engagement with the cam surface 107' and before the cam surface 97 becomes effective, and also that the point will still engage teeth an instant after the roller leaves the cam projection. It will be seen that there can be no restoration of the typewriter key to its normal position until the key has been depressed its proper distance to carry the wing frame teeth beyond the locking web point. 125 130

If this is not done and the key released the parts will not be restored because of the dimensions of the locking web and wing frame before specified. If the key has already been sufficiently depressed it may return to its normal position by spring mechanism well known in typewriting machines, and the cam arm 96 and wing frame 94 will move toward their normal position, the roller shaft again being carried into engagement with the cam surface 107' to cause backward rotation of this roller shaft about the shaft 89. The effect of this rearward rotation of the shaft 89 and the arms 88 thereon will not be felt by the link and bell crank mechanism connected with the segmental gear on account of the slot 86 in the link 85, the post 87 passing to the lower end of said slot as the shaft roller passes over the cam surface 107' and moving back to the upper normal position shown in Fig. 4 when the shaft roller drops into engagement with the surface 108. The cam arms upon release of the key will at first not be actuated but when the lower end of the slot 99 reaches the post 98 the goose-neck will be disengaged from the corresponding cam roller 101 and by means of springs 115, the shaft 69 and the segmental gear thereon will return to their normal position. The locking web having become disengaged from the teeth upon complete depression of the key allows return passage thereby of the teeth 110, but there can be no subsequent depression or forward rotation of the wing frame 94 unless the key has been sufficiently restored and the wing frame teeth carried rearwardly beyond the locking web point. This locking web with the teeth therefore prevents the occurrence of errors due to insufficient actuation or restoration of the keys and parts actuated thereby. It is also very important that the indicating mechanism and the actuating wheel 49 be locked against rotation except when a calculation is to be performed, as otherwise there might be accidental displacement thereof and consequently error. It is also very important that any lateral movement of the indicating mechanism be prevented while the actuating wheel 49 and the indicating mechanism driven thereby are in operation to perform a calculation. These two very important features are accomplished upon actuation of the roller shaft 92 by the cam projection 107 upon depression of a key.

Extending upwardly from the shaft 89 is an arm 116 from whose end extends the post 117 engaging in the elongated slot 118 at the end of the link 119 pivoted at 120 to the end of a lever 121 pivoted on the shaft 122 extending from the driving mechanism frame. Extending rearwardly from this lever near the pivot thereof is the locking arm 123 adapted for engagement in the slots 124 be-

tween the teeth 125 cut in the lower forward edge of the supporting frame 10, these teeth having the same spacing as the slots 38 at the upper edge of the frame 10, or, in other words, having the same spacing as the escapement carriage. Upon depression of a key the roller 92 engages the cam surface 107', as before described, to cause rotation of the roller shaft about the shaft 89 whereby the arm 88 and the intervening mechanism 75 is moved to swing the segmental gear into mesh with the driving gear. At the same time also the arm 116 is rotated rearwardly to move the link 119 and to rotate the frame 121 about its pivot shaft 122. Upon rotation of this frame 122 the end of the arm 123 is brought into engagement with the corresponding slot 124 and the carriage is prevented from escaping, and the indicating mechanism frame securely held against lateral displacement before the cam arm 96 causes rotation of the actuating lever to cause rotation of the segmental gear. In other words, the segmental gear will not be moved to cause actuation of the indicating mechanism until the indicating mechanism framework is securely locked against lateral displacement. The escapement carriage and the supporting frame 10 may also become displaced or distorted on account of lost motion or other causes, and to insure proper calculations these parts must be in proper position before actuation of the calculating mechanism. The edges of the teeth 125, therefore, are beveled; as best shown in Fig. 100 5, and the end of the locking arm 123 is also beveled, so that entrance of the arm 123 into the proper space is assured and the supporting frame 10 connected with the escapement carriage first into proper position should 105 these parts have become slightly displaced. The escapement carriage and frame 10 are securely locked against further movement by the arm 123 during the entire downward movement of the number key. At the end 110 of the downward stroke the roller shaft drops from the surface 107' to the surface 109, and the carriage may escape.

Pivoted to the shaft or post 126 is a bell crank lever 127 having at the end of its arm 115 128 a tooth 129 for engagement with the teeth of the actuating wheel 49. The other end 130 of the lever terminates in a post 131 engaging in the slot 132 through the lever frame 121. Upon depression of a number 120 key and the consequent rotation of the lever 121 the bell crank 127 will be rotated to withdraw the tooth 129 from engagement with the wheel 49 just before the cam arm 96 becomes effective to rotate the engaged actuating arm 100, and at the end of the stroke upon return of the roller shaft to the surface 109 the lever frame 121 and the bell crank 127 are returned to their normal position by the spring 133. This is at the end of a calcu- 130

lation, and the arm 123 being withdrawn from the corresponding slot 124 the escapement mechanism of the machine becomes effective and moves the carriage. A weight 5 134 might be employed at the end of the arm 128 of the lever 127 to cause more rapid response and to give greater power to force the tooth 129 between the teeth of the wheel 49. Thus the indicating mechanism is normally 10 locked against actuation and held so until the segmental gear is rotated and the escapement carriage and frame 10 are securely locked against displacement almost immediately upon depression of a key and held 15 thus rigidly during the entire calculating period. Upon release of the key the roller shaft 92 upon engagement with the cam extension 107 is rotated rearwardly about the shaft 89 and the arm 116 on the shaft 89 rotated forwardly. The slot 118 in the link 119, however, performs the same function as the slot 86 in the link 85 of the segmental gear swinging mechanism, and the post 117 20 on the arm 116 merely moves along the slot 118 without consequent motion of the lever frame 121 and when the shaft roller again reaches the surface 108 the post returns to 25 its normal position at the rear end of the slot 118.

30 If a number key is intended to be actuated but is not depressed its entire stroke the locking web 111, as before described, will prevent restoration of the key. The operator noticing that the key does not restore in this case 35 can further depress the key through its full stroke and the desired number will be entered in the indicating mechanism. If a key is struck unintentionally and throughout its full stroke and a number unintentionally 40 added or subtracted in the indicating mechanism the error can easily be rectified by moving the gear controlling lever 62 to its other position. For instance, if the gearing is set for adding and a number key is unintentionally struck the gearing mechanism 45 can then be moved to the subtracting position and the same key struck which will result in the restoration of the indicating mechanism to its position before the key was 50 unintentionally struck. If, however, a key is unintentionally struck and insufficiently moved so that the locking web 111 locks the key against restoration, or in the event that two keys are struck simultaneously and 55 locked by the locking web against restoration, means must be provided for releasing these keys and for causing the error introduced by such unintentional key actuation to be rectified or taken out of the indicating 60 mechanism.

It is very common to accidentally strike two or more keys at the same time, and on account of interference between the type actuated by the key these keys can not be de-

pressed their full distance and will consequently be locked against restoration. This simultaneous actuation of the keys causes a resultant rotation of the segmental gear and the introduction of a corresponding error in the indicating mechanism, and to rectify this 65 error the segmental gear must be rotated in a reverse direction to its normal or initial driving position to remove the error before the mechanism is operated which will swing the segmental gear from meshing engagement with the driving gears.

As best shown in Figs. 10, 17 and 18 lever frame 135 is pivoted to the shaft 136 bearing in the frame 137 secured to the frame 43. An arm 138 extends from the frame 135 80 through the opening 139 in the frame 43 and is adapted for engagement with the tongue 140 extending from the hub 141 which also supports the locking web 111. Adjacent to the lever frame 135 is a second lever 142 85 on the shaft 136 having at its one end the projection or post 143 normally engaging the extension or shoulder 144 on the frame 135. A spring 146 connecting between the frame 43 and the lever frame 135, normally serves 90 to hold the shoulder 144 against the post 143 and the corresponding end of the lever 142 against the leaf spring 147 secured to the frame 43. The other end of the lever 142 terminates in a hook 148. Extending from 95 the shaft 89 are the posts 149 and 150, the post 149 being adapted to be caught by the hook 148 upon depression of the lever 135 and the post 150 being adapted to be engaged by the shoulder 151. Pivoted to the 100 post 152 extending from the frame 135 is a pawl frame 153 from whose tail end extends the post 151, normally held within the notch 154 in the lower edge of the lever frame 135 by the spring 155, said pawl frame having at 105 its front end a tooth 156 adapted for engagement with a tooth 157 extending from the shaft 69.

Normally all the parts just described are in the position shown in Figs. 10 and 17. If now 110 the one key is unintentionally lightly struck and is locked by the locking web against restoration, or if two or more keys are simultaneously struck and locked against restoration, then, as shown in Fig. 18 the operator 115 presses on the finger piece 158 to rotate the front part of the lever frame 135 downwardly and the arm 138 upwardly into engagement with the tooth 140. As the key was depressed the cam projection 107 was brought 120 into engagement with the roller shaft 92 and this shaft rotated about the shaft 89 which also caused the teeth 149 and 150 to be rotated rearwardly. Engagement of the extension 138 with the tooth 140 releases the 125 locking web 111 from the locking teeth 110, and the key is released to restore itself. The shaft 89 whose rotation controls the swinging

mechanism of the segmental gear is held against rotation because the hook 148 upon depression of the lever 135 is moved to catch the post 149, this movement of the hook being caused by the pressure of the spring 147 against the other end of the lever 151. Upon depression of the lever frame 135 the pawl tooth 156 and the tooth 157 will merely move by each other without causing movement of the actuating shaft 69, as the pawl frame is held against rotation by the spring 155 only. Upon return of the lever frame 135, however, to its normal position, the pawl frame will be locked by the engagement of the pin 151 in the notch 154, and the tooth thereon coming into engagement with the tooth 157 the shaft 69 is rotated back to its normal position to return the segmental gear to its normal position to correct the error unintentionally introduced upon insufficient actuation of the one key or simultaneous actuation of the several keys. The hook 148 is released from the post 149 upon reengagement of the shoulder 144 with the upper end of the lever 152, but this disengagement does not take place until the pawl tooth has passed upward sufficiently to cause rotation of the segmental gear back to its normal position. In other words, the segmental gear is prevented from unmeshing from the driving gears until it has been sufficiently rotated to rectify the error. As before stated, the post 150 is engaged by the shoulder 151 at the end of the downward stroke of the lever 135, the purpose of this being to cause a slightly additional rotation of the shaft 89 to lift the shaft roller from the cam surface 107 which reduces the friction and allows the key and ring frame to be more readily restored. The lever 135 is held in its normal position by the spring 159, but to insure more positive operation of the correcting parts the lever frame may be returned manually to its normal position. The carriage is also locked against escapement by the arm 123 until the error is corrected.

In Figs. 8 and 9 I have shown two positions of other controlling mechanism which enables the operator to release the calculating mechanism from the segmental gear, said mechanism also serving to prevent actuation of the segmental gear shaft otherwise than by striking the keys. A lever frame 160 has a slot 161 near its center in which engages the pivot pin 162. The rear end 163 of the lever extends through the opening 164 through the frame 43 and is adapted for engagement with the tooth 165 extending from the locking web hub 141. In the normal position of this lever as shown in Fig. 8, the tooth 165 will not be engaged by the end 163 and the operation of the locking web 111 will not be interfered with. A second lever 166 is pivoted at its end about the pivot 162, and at an intermediary point 167 is connected by a spring 168 with the frame 43, 65 resting against a pin 169 projecting from the extension 170 from the lever 160, this being connected by a spring 171 with the frame 43. The end 172 of the lever 166 is adapted upon downward rotation of the lever 160 to 70 engage with the pin 173 extending from the shaft 89. When the lever 160 is rotated downwardly to the position shown in Fig. 9, the end 163 by engaging the tooth 165 rotates the locking web 111 from the path 75 of the teeth 110, and the spring 168 pulls the lever 166 to carry the end 172 into engagement with the pin 173 to cause the roller shaft 92 to be rotated upwardly from the path of the cam projection 107, this rotation of the shaft 89 being permissible on account of the slot 86 in the link 85 connected with the segmental gear swinging mechanism. A post 174 extends from the end 163 and is adapted for engagement at 80 either side of the head 175, and to set the lever it is drawn slightly forward and upon release will be held at either side of the head 175 by virtue of the springs 168 and 171. Upon actuation of a key after setting of the lever as shown in Fig. 9, the goose-necks will be actuated to rotate the shaft 69 and the segmental gear thereon, but as the roller shaft 92 has been carried from the path of the cam projection 107 the segmental gear 95 would not be brought into meshing engagement and therefore no actuation of the actuating wheel or indicating mechanism will result. A third lever 176 is pivoted to the shaft 177 below the lever 160. The upper 100 arm 177' of this third lever is held in engagement by the spring 178 with a post 179 extending from the lower end of the extension 170. The lower arm 180 of this third lever is normally directly before the roller shaft 105 92. A tooth 181 extends forwardly from the lever frame 176 above the shaft 177 and a shoulder 182 on the arm 183 extending from the shaft 69 is normally in engagement with this tooth so that actuation of the actuating 110 levers 100 and of the shaft 69 is normally prevented. Directly upon depression of a key, however, the roller shaft 92 is engaged by the cam projection 117 and pushed against the arm 180 of the lever 176 to rotate this 111 lever to withdraw the tooth 181 from the shoulder 182 to allow actuation of the levers 100 by the goose-neck frames to rotate the segmental gear. Depression of the lever 160, however, causes the roller shaft 92 to 120 be moved from the cam projection 107 but the shaft 69 is unlocked as the post 179 is carried against the end 177 of the lever 176 and the keys may then be actuated. A projection 185 also extends from the shaft 125 69 and by striking against the lower edge 186 of the end wall 41 limits the return motion of the actuating levers 100. This man-

ner of locking the shaft 69 against rotation until a key is struck and limiting the return movement of the actuating levers prevents undesirable actuation of the parts due to 5 jarring or rebounding.

The totalizer mechanism best shown in Figs. 3, 4, 5 and 11 is contained between the side walls 32 and 33, these walls as before stated, being provided at their rear edges 10 with the V-shaped tongues 34 and 35 which engage in the channels 29 and 30 of the traveling frame 10. A horizontal shaft 187 extends between the side walls at the front and near the middle thereof, and rotatably 15 mounted thereon are the number wheels 188, each provided with a gear wheel 189. To the rear of this shaft and slightly below it is another horizontal shaft 190 extending between the side walls and secured thereto, 20 and rotatably mounted on this shaft 190 are a plurality of totalizer gear wheels 191, each meshing with the gear of the corresponding number wheel, the teeth of these 25 gears extending below the lower edge of the side walls of the frame 31, and as this frame is carried horizontally across the machine and over the driving and actuating wheel 49 this actuating wheel will successively mesh 30 with the totalizer gears and upon depression then of a key the engaged totalizer wheel will be rotated to revolve the corresponding number wheel a corresponding number of 35 divisions. Although any gearing relation may be employed the totalizer gears are shown as provided with thirty teeth and the gears on the number wheels are provided with ten teeth making the gearing proportion three to one, and for every one third of a revolution of a totalizer gear the number 40 wheel will turn one revolution.

Secured to the left face of each totalizer gear is a thin gear plate 192 having three teeth 193 displaced 120 degrees, and adjacent to this gear plate is a cam plate 194 having three notches 195 also displaced 120 degrees and disposed directly opposite the teeth, the diameter of this cam plate being slightly less than that of the gear plate, the gear plate and cam plate constituting part of carryover 45 mechanism. Above the totalizer gear shaft is a third shaft 196 and a fourth shaft 197, these two shafts being at equal distances from the totalizer gear shaft and parallel thereto. On each of these shafts are mounted sets of carryover and locking gear mechanism, each set consisting of a pinion plate 198, a starwheel 199 and a carryover gear mechanism consisting of the gearing pinion 200 and the adjacent similar pinion 200'. The members 198, 199 and 200 are secured together, while the member 200' is loosely pivoted on the shaft with respect to the member 200, but by means of locking engagement, which I shall later describe, these members 200 and 200' are normally held together to form practi-

cally an integral pinion. The pinion plate 198 has ten teeth to mesh with the carryover teeth 193 on the gear plate 192 secured to a totalizer gear. The star wheel 199 is provided with ten circular concave peripheral 70 notches 201 having the same radius as the cam plate 195, this star wheel being in engagement with the cam plate secured to the corresponding totalizer gear wheel. The pinion part 200' of each set is in mesh with the totalizer gear adjacent to the totalizer gear with whose cam plate and gear plate the star wheel and pinion plate of the set are in engagement.

Normally a concave surface of each star wheel is in intimate engagement with the unbroken cam surface of the corresponding cam plate secured to the corresponding totalizer gear, and when in such position there can be no rotation of the carryover set on account of the greater radius at the points 202 between 85 the concave surfaces, but when a notch 195 of the cam plate arrives below one of these points additional space is afforded to allow for this longer radius, and the carryover tooth 193 disposed opposite the particular 90 cam plate notch upon meshing with the pinion plate can rotate this pinion plate and the star wheel and carryover wheel secured thereto. This rotation is transferred through the carryover pinion parts to the adjacent totalizer gear wheel. Thus at every ten advancements of one totalizer gear a carryover tooth 193 will engage the pinion plate 198 on the corresponding carryover set and at the same instant the star wheel is released, 95 whereupon the carryover gear, which engages the teeth of the next adjacent totalizer gear, will cause rotation of this adjacent gear. Owing to the dimensions of the gears this adjacent gear will be advanced to cause 100 the engaged number wheel to advance one number. In other words, at each rotation of one number wheel from zero to 9 the next actuation thereof will move it to indicate zero, and at the same instant the carryover set 105 just described will be actuated to move the next adjacent totalizer number wheel one number. To afford more compact arrangement of the mechanisms within the side walls 32 and 33 the carryover sets are staggered on 110 the shafts 196 and 197.

As the slightest touch would be sufficient to displace the totalizer gears and engaging mechanism it is very important that they be locked against rotation or displacement except at the instant that a calculation is to be performed. For this purpose I provide a plurality of locking levers 203 pivoted on a common shaft 204 secured to the rear of the totalizer shaft 190. On the upper part of each arm is pivoted a locking pinion 205 adapted for engagement with the carryover pinions 200 and 200' of a carryover set, the locking pinion being wide enough to mesh with both these carryover pinion parts. This locking 115

wheel is the means before referred to for normally locking the pinion part 200' to the part 200. Upon engagement of a carryover tooth 193 associated with one totalizer gear with the pinion plate 198 of the corresponding carryover set the locking wheel although in engagement with the parts 200 and 200' will not prevent rotation thereof and the adjacent totalizer gear will be rotated, but this adjacent totalizer gear, however, meshes only with the part 200' and cannot be directly rotated because the locking wheel engaging both the part 200' and part 200 locks the part 200' against the part 200, which part 200 is locked against rotation by virtue of the engagement of a circular notch of the corresponding star wheel with the circular cam-surface secured to the other totalizer gear. Thus normally each totalizer gear is locked against direct displacement and the possibility of errors practically eliminated. To allow calculations to be carried on, however, the locking wheel must be released from the carryover set whose corresponding totalizer gear is about to be rotated by the actuating gear 49. Each locking arm or lever therefore terminates at its lower end below the shaft 204 in a projection or finger 206 arranged in a straight horizontal line and adapted as the totalizer frame travels to pass by in front of the end 207 of the actuating arm 208 extending upwardly from the lever frame 121 associated with the driving mechanism.

As before described, the lever frame 121 is revolved about the shaft 122 upon striking of the keys and the end 207 will, therefore, be carried forwardly when a key is struck into engagement with the finger 206 of the locking lever associated with the carryover set of the totalizer gear to be actuated upon the depression of the particular key, the adjustment being such that the locking wheel is moved from locking engagement just before the segmental gear will cause rotation of the engaged totalizer gear. As the first totalizer gear to the right is not preceded by a carryover set other means must be provided for normally preventing unintentional or accidental displacement thereof, this means being shown in Fig. 12, consisting of a bell crank lever 209 also pivoted to the shaft 204 and having a finger 210 in alignment with the fingers of the locking levers 203. An arm 211 extends forwardly and has a tooth 212 for engagement between the teeth of the first totalizer gear, and normally held in engagement therewith by the spring 213 connected between the arm 211 and the frame of the totalizer. Springs 214 connected between the totalizer frame and the arms 203 serve to normally hold the locking wheels 205 in engagement with the carryover pinions of the corresponding carryover sets.

To prevent displacement of the locking wheels when the locking arms are raised, I

provide bars or wires 215 and 216 extending from a common hub 215' pivoted to the shaft 204. A spring 217 secured to the framework holds these wires in engagement between the locking gear teeth. When a locking arm is actuated the wires are raised to release the other locking gears so that the totalizer gears may carry over, the gear on the raised arm being however locked. To rotate the wire frame to release the locking gears upon actuation of the first totalizer gear, the lever 209 has an extension 210' for engaging the wire frame. To prevent undue friction of the locking wheels with the carryover pinions abutment screws 218 extending through the bar 219 are provided to form an abutment for the ends of the locking levers.

Secured in a horizontal position to the driving mechanism frame is a detaining bar 220, this bar extending upwardly to engage the front of the fingers 206 and 210 on the locking arms. In front of the end 207 of the arm 208, however, a slot or passageway 221 is cut in this bar 220 and only the locking lever whose finger is about to be engaged by the end 207 can be actuated, all the other locking bars being themselves locked as their fingers are held by the bar 220.

The number wheels and the totalizer gears are placed in groups; for example units group, thousands group, millions group, and so on, there being a space between each group of totalizer gears, and thus when the numbers are printed on the sheet they will be properly grouped without the necessity of printing periods or commas. Thus the operator wishing to strike off a sum on the keys starts say in the thousands column and strikes the numbers in the thousands division, whereupon she must strike the spacing key before proceeding to strike off the numbers in the hundreds group and so on. If she should neglect to space and should strike a number key instead there will be confusion and error. To prevent this I provide extensions or rigid fingers 222 between the groups of actuating fingers of the locking levers 203. When a spacing division is now reached and the operator should attempt to strike a number key instead of the spacing bar the end 207 of the arm 208 will strike the rigid finger 222 and the number key cannot be depressed owing to the inability of the lever frame 121, the intervening mechanism and the shaft 29 to rotate, the roller shaft becoming then rigid, and upon engagement with the cam projection 107 preventing further depression of the key. This immediately notifies the operator that she must depress the spacing key before further calculations can be made. To align the totalizer gears to insure easy and proper meshing engagement with the actuating gear 49 a properly beveled tooth 224 extends from the driving mechanism frame and disposed in advance of the actuating wheel 49. The

totalizer gears about to be carried into mesh with the actuating gear 49 are engaged by this tooth and properly alined, and the teeth of the driving wheel 49 also extend a distance 5 over the side and their entrance edges are properly beveled as best shown in Figs. 3 and 4. The entrance edges of the gears 52 and 56 also extend a distance over the side and are beveled as shown to insure easy and proper 10 meshing connection of the segmental gear therewith.

As before stated, the totalizer frame is adjustable along the traveling frame 10, the locking lever 37 and the slots 38 serving for 15 this purpose, and the starting position of the totalizers may be adjusted to correspond with that of the typewriting machine. To render it unnecessary for the operator to strike off the spacing on the spacing bar of 20 the typewriter to bring the totalizer gear into engagement with the actuating gear 49 tabulating mechanism may be used for this purpose, and Figs. 1 and 15 show the well known form of tabulating mechanism employed in 25 conjunction with Remington typewriters. The tabulating keys 225 are disposed in a horizontal row at the front of the machine and connect by rods 226 with the levers 227 pivoted at 228 and terminating at their upper 30 end in the escapement fingers 229. Mounted on the traveling carriage of the typewriter is a bar 230 provided with teeth 231 whose pitch is equal to the pitch of the escapement teeth of the typewriter. The 35 escapement fingers 229 are grouped in the rear of this actuating bar and are spaced to correspond with the teeth 231. Abutments 232 are adapted for adjustable insertion in the teeth of the rack 230 and are spaced 40 thereon to correspond with the spacing between the totalizer gears and the starting point of the typewriting machine. By the proper spacing of these abutments it is necessary only for the operator to depress the 45 proper tabulating key and the escapement carriage will travel directly to bring the corresponding totalizer gear into mesh with the driving gear. It is also evident that instead of only one totalizer as shown a greater number 50 can be inserted on the frame 10 to be actuated by the driving mechanism.

Ordinarily the distance between the totalizer gears of a group should be equal to the spacing distance of the machine so that upon 55 each escapement the next gear will be brought in proper meshing relation with the driving wheel 49, and the spacing between groups should be equal to twice the spacing distance of the machine. In some machines, 60 however, the spacing distance is very small, in this particular machine shown being one tenth of an inch. A great deal of mechanism, however, must be crowded in between gear wheels and at the same time this 65 mechanism such as gear wheels and gear

plates must be sufficiently wide to insure proper meshing relation. As before described, a gear plate and cam plate are secured to one side of each gear wheel, and between each gear wheel and the adjacent gear wheel there must be space to receive the number wheel and also the number wheel gear which meshes with the totalizer gear. There must also be room between these gear wheels for the pinion plate, star wheel and carryover pinion parts of the corresponding carryover set. These gear plates and gear wheels must be of sufficient width to insure proper meshing relations as before stated. It can easily be seen however, that with but one tenth of an inch available these parts might therefore be too small to insure proper coacting relations and error might result. The space between groups, however, is considerably larger than between gear 75 wheels.

In Fig. 16 I have diagrammatically shown improved spacing for the gear wheels which takes the surplus space from between the groups and distributes it between the totalizer gears. The gear wheels and the various parts attached thereto are shown, and the relative positions of the actuating wheel 49 as the totalizer frame travels are also shown. Instead of making the distance s between gear wheels equal to the spacing distance of the machine this is slightly increased and the distance s' between the groups is correspondingly diminished. In other words, the increased space added between gears of a group is subtracted from the space between groups so that the total distance between all the gears remains unchanged. The effective meshing width of the actuating wheel 49 is also sufficiently greater than that of the gear wheels so that there will always be meshing engagement. The first position of the wheel 49 is shown in full lines and the subsequent positions relative to successive gears are shown in dotted lines. The first gear wheel 105 then engages at the center of the wheel 49. The next gear wheel engages to the left of the center, the next wheel to the right of the center, the next gear wheel again at the center and so on. Thus without losing any efficiency 110 I am enabled to increase the available space between gear wheels sufficiently to acquire proper dimensions for the delicate working parts. The totalizer parts may be further protected by the covering 233 which fits about the front and lower edges 234 and 235 of the side walls 32 and 33 and suitably secured thereto. In the front of this covering a number of openings 236 may be provided in a horizontal row to exhibit the row of numbers on the totalizer number wheels. An indicating plate or scale 237 may also be provided on the totalizer frame having the division lines 238 corresponding to the grouping of the gear wheels, and a pointer 239 secured to 115 120 125 130

the typewriter frame will indicate on this scale which totalizer gear is being actuated upon depression of a key. The driving mechanism parts may also be concealed and protected by 5 a covering 240 having the openings 241 and 242 through which extend the ends 158 and 243 of the controlling levers 135 and 160 respectively, the end 243 being in the form of a knurled head whereby the lever 160 may be 10 better actuated, it being necessary to pull and push this lever while rotating it.

The operation of the device is now apparent. For illustration, suppose it is desired to add a column of sums, then, after the 15 totalizer frame is properly adjusted so that the printed numbers will appear at the proper position on the sheet, and the totalizer number wheels all indicate zero, the proper tabulating key for the first sum is struck, where- 20 after the number keys of the machine are successively struck to place the remaining numbers of the sum on the totalizers. The escapement carriage is then returned to its initial position, the printing roller being ad- 25 vanced the required distance at the same time. The proper tabulating key is struck for the second sum and the proper number keys struck, this second sum appearing on the sheet under the first sum and in proper 30 alinement therewith, this second sum, how- ever, being added to the first on the totalizer. In the same manner the remaining sums are accumulated on the totalizer and printed in 35 alinement on the sheet. The totalizer at the end of the calculation will indicate the total 40 sum of all the numbers and this sum is then placed below the column of sums on the sheet, the proper mechanism being first, however, actuated to reverse the rotation of the driving mechanism and the result will be 45 that the number wheels will be returned to zero and the accumulated sum total of the added numbers will be placed on the sheet below the added numbers. The different 50 mechanisms and their operations for producing these results have been sufficiently described before and it will not be necessary to repeat them here.

I thus provide a very useful and efficient 55 device for performing calculations of addition and subtraction which may be removably connected with any typewriting machine without in any way interfering with the ordinary operation of the machine. The con- 60 struction and arrangement of these parts are very compact as described, and produce a very neat appearance.

The various locking features are such that 65 practically all errors due to rebounding, mo- 70 mentum or accidental contact with the parts are prevented, while the various adjusting and correcting mechanisms employed are so arranged and constructed that they may be quickly and readily actuated to restore false 75 or accidental actuations and to correct in the

indicating mechanism any errors resulting 70 therefrom. The feature of locking the car- riage against escapement until the desired calculations are performed in the totalizer is also very important.

Variations in the construction and arrangement from that shown and described may be 75 made without departing from the spirit of my invention. I do not, therefore, wish to be limited thereto.

What I claim as new and desire to secure by Letters Patent is:

1. In calculating mechanism for attachment to a typewriting machine, the combination with a totalizer frame connected with 80 the escapement carriage of the machine and comprising a plurality of totalizer gears pivoted in a horizontal row within the totalizer frame, of a main driving gear pivoted to the machine frame for meshing successively with 85 the totalizer gears as the totalizer frame travels with the escapement carriage, a seg- mental gear, a supporting shaft to which the segmental gear is pivoted to swing laterally thereon, means associated with said shaft and 90 adapted upon actuation of a key of the ma- chine for causing rotation of the shaft with the segmental gear, means associated with the keys and adapted upon initial actuation thereof to cause lateral swing of the seg- 95 mental gear into driving relation with the main driving gear before the segmental gear is rotated, a locking arm pivoted to the ma- chine frame and associated with the keys, and slots spaced on the totalizer frame, initial 100 actuation of the key causing said locking arm to be engaged in one of said slots to lock the totalizer frame against escapement during the time that the segmental gear is rotated to cause actuation of the engaged totalizer 105 gear.

2. In a calculating machine, the combina- 110 tion with a totalizer frame, of means for caus- ing travel thereof across the machine, calcu- 115 lating mechanism within the totalizer frame, a plurality of totalizer gears for the calcu- lating mechanism disposed in a horizontal line, driving mechanism for the machine asso- 120 ciated with keys thereof and adapted for suc- cessive engagement with the totalizer gears as the totalizer frame travels, means nor- mally locking the calculating mechanism against actuation, means normally locking the driving mechanism against actuation, means upon initial actuation of a key for re- 125 leasing said locking means from the driving and calculating mechanisms, and means upon further actuation of the key for causing op- 130 eration of the released driving and calculating mechanisms whereby a calculation is performed.

3. In a calculating machine, the combina- 130 tion with a totalizer frame, of means for caus- ing travel thereof, calculating mechanism supported from the totalizer frame and

adapted to travel therewith, driving mechanism associated with keys of the machine and normally out of driving relation with the totalizer mechanism, locking mechanism 5 normally locking the totalizer mechanism against actuation, additional locking mechanism, means upon initial actuation of a key for causing said additional locking mechanism to be actuated to lock the totalizer frame 10 against travel, means for then causing release of the first locking mechanism from the totalizer mechanism, means during actuation of the locking mechanisms for causing said driving mechanism to be brought into 15 driving relation with the totalizer mechanism, means upon further actuation of the key for causing actuation of the driving mechanism and of the totalizer mechanism in driving relation therewith, and means upon release of the key for causing the driving mechanism and the locking mechanism to be restored to their normal positions.

4. In calculating mechanism for attachment to typewriting machines, the combination 25 with a totalizer frame connected with the escapement carriage of the machine to travel therewith, of driving mechanism mounted on the frame of the machine and associated with keys of the machine, means 30 for normally retaining the driving mechanism out of driving relation with the totalizer mechanism on the totalizer frame, locking means for normally locking the totalizer mechanism against actuation, additional 35 locking means associated with the keys for normally allowing escapement of the totalizer frame, means upon initial actuation of a key for releasing the locking mechanism from the totalizer mechanism, means for 40 causing actuation of the additional locking mechanism to lock the totalizer frame against travel independently of the escapement mechanism of the machine, means for causing the driving mechanism to be brought 45 into driving relation with the totalizing mechanism, said locking mechanism and means for bringing the driving mechanism into driving relation being actuated substantially simultaneously, and means upon 50 further actuation of the key for causing actuation of the driving mechanism to cause actuation of the totalizing mechanism, said locking and driving mechanisms being returned to their normal positions at the end 55 of a key actuation.

5. In a calculating machine, the combination 60 with indicating and calculating mechanism carried on a supporting frame, of means for causing advancements of the supporting frame, driving mechanism supported from the frame on the machine, keys for the machine, cam mechanism intervening between said keys and the driving mechanism for causing actuation of the driving mechanism 65 upon depression of a key, a shaft pivoted to

the machine frame, cam mechanism adapted upon actuation with the key to cause rotation of said shaft, and a locking lever pivoted to the machine frame and having connection with said shaft, actuation of a key causing 70 first actuation of the cam mechanism associated with said shaft and locking lever to lock the supporting frame to the machine frame to prevent advancements thereof and causing then actuation of the cam mechanism 75 associated with the driving mechanism to cause actuation of the driving mechanism and the indicating and calculating mechanism connected therewith.

6. In a calculating machine, the combination 80 with indicating mechanism carried on a supporting frame adapted to travel, of driving mechanism supported from the machine frame and associated with the indicating mechanism, keys for the machine, mechanism connected with said keys and with the driving mechanism adapted upon depression of a key to cause actuation of the driving mechanism and of the indicating mechanism 85 connected therewith, a pivot shaft, an actuating arm secured to said shaft, cam frames actuated upon depression of keys for engaging said actuating arm to cause rotation of said pivot shaft, a locking lever pivoted to the machine frame and connected through 90 intervening mechanism with said pivot shaft, initial depression of a key causing first rotation of said pivot shaft to move the locking lever into locking engagement with the supporting frame for the indicating mechanism 95 whereby said supporting frame is locked against advancements, and further depression of the key causing actuation of the connecting mechanism to cause actuation of the driving mechanism and the indicating mechanism connected therewith, the locking engagement of the locking lever with the indicating supporting frame being maintained throughout the entire actuation of the indicating mechanism by the driving mechanism. 100

7. In a calculating machine, the combination 105 with indicating mechanism mounted on a supporting frame adapted to travel, of driving mechanism associated with the indicating mechanism, keys for the machine, 110 cam mechanism connected with the keys and with the driving mechanism and adapted upon depression of a key to cause actuation of the driving mechanism and indicating mechanism connected therewith, a cam 115 frame connected with each key, a shaft to which said cam frames are pivoted, a cam surface on each cam frame, a pivot shaft, an actuating arm secured in said pivot shaft and disposed in the path of said cam surfaces, 120 actuation of a key and of a cam frame causing engagement of the cam surface with said arm to cause rotation of the pivot shaft, a locking arm pivoted to the machine frame, lever mechanism between said arm and an 125

5 arm extending from the pivot shaft, initial actuation of a key causing rotation of the cam frame and the cam surface thereon into engagement with the actuating arm to rotate the pivot shaft and lever mechanism to cause the locking arm to be carried into locking engagement with the supporting frame for the indicating mechanism whereby said supporting frame is locked against advancement, and further actuation of the key causing 10 the other cam mechanism to actuate the driving mechanism to cause operation of the indicating mechanism, there being no actuation of the driving mechanism to move the 15 indicating mechanism until said locking arm has been carried into locking engagement.

8. In a calculating machine, the combination with indicating mechanism mounted on a supporting frame adapted to travel, of driving mechanism for the indicating mechanism supported from the machine frame and normally held out of driving relation with the indicating mechanism, keys for the machine, a cam frame for each key having a 20 cam surface, a pivot shaft, an actuating arm secured to said pivot shaft and disposed in the path of the cam surface, mechanism intervening between said pivot shaft and the driving mechanism, and mechanism intervening between said keys and the driving mechanism, actuation of a key causing first actuation of a cam surface to rotate the pivot shaft and to cause actuation of the mechanism connected therewith and with 25 the driving mechanism to move said driving mechanism into driving relation with the indicating mechanism, further actuation of the key then causing actuation of the intervening mechanism and driving actuation of 30 the driving mechanism whereby the indicating mechanism is actuated.

9. In a calculating machine, the combination with indicating mechanism mounted on a supporting frame adapted to travel, of driving mechanism for the indicating mechanism supported from the machine frame and normally held out of driving relation with the indicating mechanism, keys for the machine, a cam frame for each key having a 35 cam surface, a pivot shaft, an actuating arm secured to said pivot shaft and disposed in the path of the cam surface, mechanism intervening between said pivot shaft and the driving mechanism, mechanism intervening 40 between said keys and the driving mechanism, actuation of a key causing first actuation of a cam surface to rotate the pivot shaft and to cause actuation of the mechanism connected therewith and with the driving mechanism to move said driving mechanism into driving relation with the indicating mechanism, further actuation of the key then causing actuation of the intervening mechanism and of the driving mechanism 45 whereby the indicating mechanism is actuated.

10. In a calculating machine, the combination with indicating mechanism supporting frame securely against travel during the time that the indicating mechanism is being actuated.

10. In a calculating machine, the combination with indicating mechanism mounted on a supporting frame adapted to travel, of driving mechanism for causing actuation of the indicating mechanism supported from the machine frame and normally out of driving relation with the indicating mechanism, gearing mechanism for the driving mechanism, a shaft to which said gearing mechanism is pivoted, cam arms extending from said shaft, a second shaft pivoted to the machine 70 frame, cam arms on said shaft connected with keys of the machine and adapted upon sufficient actuation of a key to engage the cam arms on the driving mechanism shaft to cause rotation thereof, a cam frame for each 75 key on said second shaft having a cam surface, a pivot shaft mounted on the machine frame, an actuating arm secured to said shaft for engagement with the cam surfaces on the cam frames, and lever and link mechanism connected with said pivot shaft and with the driving gearing mechanism, initial actuation of a key causing rotation of the connected cam frame to rotate the pivot 80 shaft to cause actuation of the lever and link mechanism to move the driving gearing into driving relation with the indicating mechanism, further actuation of the key causing engagement of the corresponding link arms 85 connected with the second shaft and with the driving mechanism shaft whereby said driving gearing is rotated to actuate the indicating mechanism after having been moved 90 into driving relation therewith.

11. In a calculating machine, the combination with indicating mechanism carried on a supporting frame adapted to travel, of driving mechanism normally out of driving relation with the indicating mechanism, a shaft from which the driving mechanism is 105 supported, actuating arms extending from said shaft, cam arms for engaging said actuating arms and connected with the keys of the machine, a pivot shaft for said cam arms, a cam frame also connected with the keys 110 and pivoted on said cam arm shaft, a pivot shaft, an actuating arm secured to the pivot shaft and adapted to be engaged by the cam frame to cause rotation of the pivot shaft, lever and link mechanism connecting with 115 the driving mechanism and with said pivot shaft and adapted upon actuation to move the driving mechanism into driving relation with the indicating mechanism, a locking arm pivoted to the machine frame, link and lever mechanism intervening between said locking arm and the pivot shaft and adapted upon actuation to move the arm into locking engagement with the indicating mechanism 120 supporting frame to lock said frame against 125 130

travel, actuation of a key causing first actuation of the cam frame and the mechanisms controlled thereby whereby the supporting frame is first locked and the driving mechanism carried into driving engagement with the indicating mechanism, further actuation of the key causing then actuation of the cam arms into engagement with the actuating arms whereby the driving mechanism is actuated to cause operation of the indicating mechanism after having been brought into driving relation therewith, and means upon restoration of the key to its normal position for causing release of the locking mechanism from the supporting frame and for returning the driving mechanism to its normal position out of driving relation with the indicating mechanism.

12. In a calculating machine, the combination with indicating mechanism mounted on a supporting frame, of a main driving wheel for engaging the indicating mechanism, a driving segmental gear, a shaft for said segmental gear, actuating arms extending from said segmental gear shaft, keys for the machine, cam frames connected with said key for engagement with said actuating arm, a shaft to which said cam frames are pivoted, a cam surface on the cam frames, a pivot shaft, a cam arm connected with the pivot shaft for engaging with the cam surfaces, lever and link mechanism connecting with the segmental gear and with said pivot shaft and normally disposed to hold said segmental gear out of driving relation with the driving wheel, actuation of a key causing first engagement of the cam surface with the cam arm to actuate the link and lever mechanism to move the segmental gear into driving relation with the driving wheel, further actuation of the key causing effective engagement of the cam frames and of the actuating arms on the shaft of the segmental gear whereby said gear is rotated to actuate the driving wheel and indicating mechanism connected therewith, and means upon release of the cam arm from the cam surface for restoring the link and lever mechanism to its normal position whereby the segmental gear is moved from driving engagement with the main driving gear.

13. In a calculating machine, the combination with indicating mechanism mounted on a supporting frame adapted to travel, of relatively stationary driving mechanism for the indicating mechanism, a gear wheel for the driving mechanism, a shaft for supporting said gear wheel, said gear wheel being pivoted to said shaft and adapted to swing laterally about said pivot, actuating arms extending from said gear shaft, cam arms connected with keys of the machine for engaging said actuating arms to cause rotation of the gear shaft, a cam frame connected with each

key having a cam surface, a cam arm for engagement with said cam surface, and link and lever mechanism connecting with said driving gear and with said cam arm, said link and lever mechanism being normally disposed to be normally actuated to move the driving gear laterally out of driving relation with the indicating mechanism, actuation of a key causing first engagement of the cam surface on the cam frame with the cam arm and actuation of the link and lever mechanism to move the driving gear into driving relation with the indicating mechanism, further actuation of the key causing the cam arm thereon to be carried into driving relation with the corresponding cam arm on the gear shaft whereby said gear is rotated to drive the indicating mechanism after having been carried into driving relation therewith.

14. In calculating mechanism adapted for attachment to a typewriting machine, the combination with a totalizer connected with the escapement carriage of the machine to travel therewith across the machine, said totalizer comprising a plurality of totalizer gears mounted in a horizontal row and accompanying calculating mechanisms, of comparatively stationary driving mechanism for the totalizer mechanisms, a driving gear for the driving mechanism, a shaft for said driving gear, actuating arms extending from said gear shaft, one associated with each number key of the machine, an actuating cam frame connected with each key, a shaft for said actuating cam frames, a cam arm extending from each cam frame for engaging the corresponding actuating arm extending from the gear shaft, a cam projection on each cam frame, a pivot shaft, an actuating arm secured to the pivot shaft for engagement with the cam projections, lever and link mechanism connected with said pivot shaft and with said driving gear, said link and lever mechanism being normally disposed to hold the driving gear from driving relation with the indicating mechanism, a locking arm pivoted to the machine frame, and link and lever mechanism connecting said locking arm with the pivot shaft, actuation of a key causing movement of the cam frame to first cause actuation of the pivot shaft whereby the locking arm is moved into locking engagement with the totalizer supporting frame to lock said frame against escapement independently of the escapement mechanism of the machine, and whereby said driving gear is moved into driving relation with the indicating mechanism, further actuation of the key causing the cam arm from said frame to be moved into actuating relation with the actuating arms whereby said gear shaft is rotated to drive the indicating mechanism after having been brought into driving relation therewith, said locking arm being maintained in locking en-

gagement throughout the entire movement of the indicating mechanism by the driving gear.

15. In calculating mechanism adapted for attachment to a typewriting machine, the combination with a totalizer connected with the escapement carriage of the machine to travel therewith, of an actuating gear wheel pivoted to the machine frame for engagement with the totalizer gears as the totalizer frame travels, a shaft, a segmental gear pivoted to said shaft to rotate therewith and to have lateral swinging motion thereon, keys for the machine, cam mechanism associated with said keys and with said gear shaft and adapted upon actuation of the key to cause rotation of the gear shaft, said segmental gear being normally swung away from the actuating wheel out of driving relation therewith, a locking arm pivoted to the machine frame, mechanisms associating said locking arm with the machine keys, and additional mechanism associated with the segmental gear and said machine key, initial actuation of a key causing actuation of the mechanisms to cause first actuation of the locking arm to lock the totalizer against escapement independently of the escapement mechanism of the machine and to cause the segmental gear to be swung into driving relation with the actuating gear, further actuation of the key then causing rotation of the gear shaft and segmental gear whereby the actuating gear wheel and the engaged totalizer mechanism are actuated, the locking engagement of said arm being maintained throughout the entire rotational movement of the segmental gear, said arm and segmental gear being restored to their normal position at the end of a key actuation to allow escapement of the totalizer frame and to remove the segmental gear from driving relation.

16. In calculating mechanism adapted for attachment to a typewriting machine, the combination with totalizer mechanism mounted on a totalizer frame connected with the escapement carriage of the machine to travel therewith, of an actuating wheel pivoted to the machine frame for engaging with the totalizer gears as the totalizer travels across the machine, a segmental gear, a shaft to which said gear is pivoted to swing laterally thereon and to rotate therewith, said segmental gear being normally swung to be out of driving relation with the actuating wheel, mechanism intervening between the keys of the machine and the segmental gear shaft, other mechanism between said keys and the segmental gear, a locking arm pivoted to the machine frame, and mechanism intervening between said locking arm and the machine keys, actuation of a key causing first immediate movement of the locking arm to lock the totalizer frame securely against escape-

ment independently of the escapement mechanism of the machine, said initial actuation causing next actuation of the intervening mechanism to swing the segmental gear into driving relation with the actuating wheel, and further actuation of the key causing then rotation of the gear shaft to cause rotation of the segmental gear and of the actuating wheel and totalizer mechanism connected therewith, said locking engagement being maintained until the end of the actuation of the totalizer mechanism, release of the key serving to release the arm from locking engagement and to swing the segmental gear out of driving relation with the actuating wheel. 80

17. In a calculating machine, the combination with indicating mechanism, of a main actuating wheel pivoted to the machine frame for engagement with the indicating mechanism, a segmental gear having rotational movement and lateral swinging movement to be normally swung out of driving relation with the actuating wheel, mechanism associated with the segmental gear and with the machine keys adapted upon actuation of a key to first swing the segmental gear into driving relation with the actuating wheel and then to rotate the segmental gear to cause actuation of the indicating mechanism, locking means for preventing restoration of the key unless sufficiently actuated, and lever mechanism for releasing said locking mechanism, said lever mechanism being also associated through intervening mechanism with the segmental gear to hold said gear in driving relation with the actuating wheel until said segmental gear has been returned to its normal position upon restoration of the released key. 90

18. In a calculating machine, the combination with totalizer mechanism, of driving mechanism normally out of driving engagement therewith, mechanism connected with the driving mechanism and with the keys of the machine and adapted upon depression of a key to first move the driving mechanism into driving relation with the totalizer mechanism and then to cause actuation of the driving mechanism to actuate the totalizer mechanism, locking means for preventing restoration of a key until said key is depressed its full distance, means for releasing said locking mechanism, manually operated means independent of the keys for reversing the driving mechanism to restore it to its normal position, and means for preventing said driving mechanism from moving out of driving relation with the totalizer mechanism upon reversal thereof to its normal position. 115

19. In a calculating machine, the combination with indicating mechanism, of driving mechanism therefor normally out of driving relation with the indicating mechanism,

- means upon actuation of a key of the machine for causing the driving mechanism to be brought first into driving relation with the indicating mechanism and then actuated 5 to cause actuation of the indicating mechanism, locking means for preventing restoration of an actuated key until said key has been moved the required distance, and manually operated correcting mechanism adapted upon actuation to release the locking mechanism and to lock the driving mechanism in driving relation with the indicating mechanism and to reverse the driving mechanism to its normal or initial driving position 10 before actuation thereof, and then to release the driving mechanism from driving relation with the indicating mechanism.
20. In a calculating machine, the combination with indicating mechanism, of driving mechanism therefor normally out of driving relation therewith, means upon actuation of a key for first causing said driving mechanism to be moved into driving relation and then to cause actuation of the indicating mechanism, locking means for locking the actuated key against restoration unless actuated sufficiently, manually operated correcting lever mechanism associated with the locking mechanism and the driving mechanism, means upon actuation of said correcting mechanism for releasing the locking mechanism from the key, detent means for said correcting mechanism adapted upon actuation thereof to prevent disengagement of the driving mechanism from the indicating mechanism upon release of the key by the locking mechanism, and means associated with the correcting mechanism adapted to reverse the driving mechanism to restore the indicating mechanism to its normal position, final actuation of the correcting mechanism causing release of the detent mechanism to lock the driving mechanism to be again removed from driving relation with the indicating mechanism.
45. 21. In a calculating machine, the combination with totalizer mechanism, of an actuating wheel for engaging totalizer gears of the totalizer mechanism, a segmental gear pivoted to a shaft and normally held out of driving relation with the actuating wheel, mechanism connecting the gear shaft with keys of the machine, a pivot shaft, a cam arm extending from said pivot shaft a cam projection actuated upon depression of a key for engagement with the cam arm, mechanism connecting between the segmental gear and the pivot shaft and adapted upon actuation of said shaft to move the segmental gear into driving relation with the actuating wheel, locking means for locking an actuated key against restoration until the key has been depressed a sufficient distance, a correcting lever frame, initial actuation of the correcting lever frame causing movement of the locking
- mechanism to release the key, and a detent frame normally controlled by the lever frame and adapted upon initial actuation of said lever frame to engage the pivot shaft and to lock said shaft against restoration upon release of the key to prevent release of the segmental gear from driving relation, return of said lever frame to its normal position causing reverse actuation of the segmental gear through a distance equal to the previous forward movement thereof, said detent frame being released from the pivot shaft upon return of the lever frame to its normal position whereby the segmental gear may be again removed from driving relation with the actuating wheel.
22. In a calculating machine, the combination with indicating mechanism, of driving mechanism therefor adapted to be moved into and out of driving relation therewith, mechanism controlled upon actuation of a key of the machine to move the driving mechanism into driving relation and to allow release of the driving mechanism from driving relation upon restoration of the key, means upon actuation of a key for causing actuation of the driving mechanism after having been brought into driving relation, locking means for preventing restoration of a key until sufficiently actuated, and correcting mechanism adapted upon actuation to release the locking mechanism and to prevent release of the mechanism controlling the meshing engagement of the driving mechanism, said correcting mechanism upon return to its normal position being adapted to restore the driving mechanism to its position before actuation and to then release the mechanism controlling the driving engagement of the driving mechanism to allow the driving mechanism to be again removed from driving relation with the indicating mechanism.
23. In a calculating machine, the combination with indicating mechanism, of driving mechanism therefor normally out of driving relation therewith, keys for the machine, a cam frame connected with each key and adapted for connection with the driving mechanism, depression of a key causing first movement of the driving mechanism into driving relation with the indicating mechanism and then actuation of the indicating mechanism by the driving mechanism to perform a calculation, locking mechanism adapted upon insufficient depression of a key to lock the key against restoration, correcting mechanism adapted upon actuation to engage the locking mechanism to release the key and to actuate the driving mechanism toward its normal position to withdraw the impression placed in the indicating mechanism upon forward movement of the driving mechanism, and means associated with the correcting mechanism for locking the driving mechanism to prevent disengagement thereof

from the indicating mechanism upon such return movement thereof.

24. In a calculating machine, the combination with indicating mechanism, of driving mechanism therefor, keys for the machine, a cam frame for each key, cam mechanisms for the driving mechanism for association with the cam frames, said driving mechanism being normally out of driving relation with the indicating mechanism, lever and cam mechanism associated with the gearing mechanism, actuation of a key causing first actuation of the lever and cam mechanism to move the gearing mechanism into driving relation and then causing actuation of the driving mechanism to advance the indicating mechanism, locking mechanism associated with the cam frame and adapted upon insufficient actuation of a key to engage the cam frame to prevent restoration of the key, releasing and correcting mechanism associated with the driving mechanism and with said locking mechanism and adapted upon actuation to engage the lever and cam mechanism to prevent actuation thereof to remove the driving mechanism from driving relation, further actuation of the correcting mechanism causing the locking mechanism to be released from the cam frame to allow the key to return to its normal position, and final actuation of the releasing mechanism causing the gearing mechanism to be returned toward its normal position before actuation to withdraw from the indicating mechanism the impression entered upon an advance actuation, said correcting mechanism then causing release of the cam and lever mechanism whereby the driving mechanism may be again removed from driving relation with the indicating mechanism.

25. In a calculating machine, the combination with indicating mechanism, of driving mechanism associated therewith, keys for the machine, a cam frame connected with each key, cam mechanism associated with the driving mechanism for engagement in the cam frame, additional cam and lever mechanism associated with the cam frames and driving mechanism and disposed normally to hold the driving mechanism from driving relation with the indicating mechanism, actuation of a key causing first movement of the cam and lever mechanism to move the driving mechanism into driving relation and then to cause actuation of the driving mechanism to advance the indicating mechanism, locking mechanism adapted upon insufficient actuation of a key to engage the cam frame to prevent restoration of the key, correcting mechanism adapted upon actuation to release the locking mechanism to allow restoration of the key, means associated with the correcting mechanism and adapted for locking the lever and cam mechanism to prevent movement of the driving mechanism out of

driving relation, said driving mechanism upon release of the key being allowed to return toward its normal position before actuation, and means associated with the correcting mechanism for positively returning the gearing mechanism whereby to restore the indicating mechanism to its normal position before actuation of the key, final actuation of the correcting mechanism causing release of the lever and cam mechanism to again remove the driving mechanism from driving relation with the indicating mechanism.

26. In a calculating machine, the combination with indicating mechanism comprising a plurality of gear wheels, of a segmental driving gear pivoted to a gear shaft to rotate therewith and to swing laterally thereon, actuating arms extending from said shaft, cam frames connected with keys of the machine and adapted upon actuation of the keys to engage the actuating arms to cause rotation of the driving gear shaft, cam and lever mechanism connected with the driving gear and associated with the cam frames, said cam and lever mechanism being normally disposed to hold the segmental gear in a swung position out of driving relation with the indicating mechanism gears, means upon actuation of a key and the cam frame connected therewith for causing actuation of the cam and lever mechanism to swing the driving gear into driving relation with the indicating mechanism gear wheels, means upon further actuation of the key for causing engagement between the cam frame and actuating arms whereby the gear shaft and driving gear are rotated to actuate the engaged indicating mechanism, release of a key and restoration thereof causing the driving gear to be swung from driving relation and to be rotated back to its normal position, locking means adapted upon insufficient actuation of a key to engage the cam frame to prevent restoration of the key, correcting lever mechanism adapted upon actuation to actuate the locking mechanism to release the cam frame whereby said cam frame and gear shaft may return toward their normal position, and locking means associated with the correcting lever mechanism for engaging the cam and lever mechanism before restoration of the cam frame to retain the driving mechanism in driving relation with the indicating mechanism during restoration thereof toward its normal position.

27. In a calculating machine, the combination with indicating mechanism comprising a plurality of gear wheels, of a driving segmental gear pivoted to a shaft to rotate therewith and to swing laterally thereon, actuating arms extending from said shaft, cam frames connected with keys of the machine and adapted upon actuation of the keys to engage the actuating arms to cause rotation of the driving gear shaft, cam and

lever mechanism connected with the driving gear and associated with the cam frames, said cam and lever mechanism being normally disposed to hold the segmental driving gear in a swung position out of driving relation with the indicating mechanism gears, means upon actuation of a key and the cam frame connected therewith for causing actuation of the cam and lever mechanism to swing the driving gear into driving relation with the indicating mechanism gear wheels, means upon further actuation of the key for causing engagement between the cam frame and actuating arms whereby the gear shaft and driving gear are rotated to actuate the engaged indicating mechanism, release of a key and restoration thereof causing the driving gear to be swung from driving relation and to be rotated back to its normal position, locking means adapted upon insufficient actuation of a key to engage the cam frame to prevent restoration of the key, correcting lever mechanism adapted upon actuation to actuate the locking mechanism to release the cam frame whereby said cam frame and gearing shaft may return toward their normal position, and locking means associated with the correcting lever mechanism for engaging the cam and lever mechanism before restoration of the cam frame to retain the driving mechanism in driving relation with the indicating mechanism during restoration thereof toward its normal position, and means upon restoration of the correcting mechanism to its normal position for positively returning the driving gear to its normal position before actuation.

28. In a calculating machine, the combination with indicating mechanism comprising a plurality of gear wheels, of a driving gear pivoted to a shaft to rotate therewith and to swing laterally thereon, actuating arms extending from said shaft, cam frames connected with keys of the machine and adapted upon actuation of the keys to engage the actuating arms to cause rotation of the driving gear shaft, cam and lever mechanism connected with the driving gear and associated with the cam frames, said cam and lever mechanism being normally disposed to hold the segmental driving gear in a swung position out of driving relation with the indicating mechanism gears, means upon actuation of a key and the cam frame connected therewith for causing actuation of the cam and lever mechanism to swing the driving gear into driving relation with the indicating mechanism gear wheels, means upon further actuation of the key for causing engagement between the cam frame and actuating arms whereby the gear shaft and driving gear are rotated to actuate the engaged indicating mechanism, release of a key and restoration thereof causing the driving gear to be swung from driving relation and to be ro-

tated back to its normal position, locking means adapted upon insufficient actuation of a key to engage the cam frame to prevent restoration of the key, correcting lever mechanism adapted upon actuation to actuate the locking mechanism to release the cam frame whereby said cam frame and gearing shaft may return toward their normal position, locking means associated with the correcting lever mechanism for engaging the cam and lever mechanism before restoration of the cam frame to retain the driving mechanism in driving relation with the indicating mechanism during restoration thereof toward its normal position, and means upon restoration of the correcting mechanism to its normal position for positively returning the driving gear to its normal position before actuation thereof.

29. In a calculating machine, the combination with indicating mechanism comprising a plurality of gearing mechanisms, of driving gearing mechanism for actuating the indicating mechanism, keys for the machine, cam mechanism associated with the keys and with the driving gearing mechanism, controlling mechanism associated with the gearing mechanism and with the keys for controlling the driving relation of the gearing mechanism with the indicating gearing mechanism, said controlling mechanism being normally disposed, to prevent driving relation of the driving gearing mechanism and indicating mechanism, actuation of a key causing first movement of the controlling mechanism to move the driving gearing mechanism into driving relation and then to cause rotation thereof by virtue of intervening cam mechanism to cause actuation of the engaged indicating mechanism, and correcting mechanism adapted upon wrongful actuation of a key to cause a wrongful actuation of the indicating mechanism for first locking the controlling mechanism to maintain driving relation of the driving mechanism and then to return said driving mechanism to its normal position to restore the indicating mechanism to its normal position before wrongful actuation of the key.

30. In a calculating machine, the combination with indicating mechanism comprising a plurality of gearing mechanisms, of driving gearing mechanism for actuating the indicating mechanism, keys for the machine, cam mechanism associated with the keys and with the driving gearing mechanism, controlling mechanism associated with the gearing mechanism and with the keys for controlling the driving relation of the gearing mechanism with the indicating gearing mechanism, said controlling mechanism being normally disposed to prevent driving relation of the driving gearing mechanism and indicating mechanism, actuation of a key causing first movement of the

- controlling mechanism to move the driving gearing mechanism into driving relation and then to cause rotation thereof by virtue of intervening cam mechanism to cause 5 actuation of the engaged indicating mechanism, locking mechanism adapted upon insufficient actuation of a key or upon simultaneous depression of two or more keys to lock the key against restoration, 10 correcting lever mechanism adapted upon actuation to release the locking mechanism from the key, a locking arm associated with the correcting mechanism and normally held thereby out of engagement with the controlling mechanism for the driving gearing mechanism, actuation of the correcting mechanism allowing movement of the locking arm to lock the controlling mechanism before release of the key by the locking 15 mechanism whereby the gearing mechanism is prevented from moving out of driving relation with the indicating mechanism, restoration of the key then upon release allowing also return of the driving mechanism toward its normal position, and means upon release of the correcting mechanism for engaging with the driving mechanism to positively restore said mechanism to its normal position before actuation, 20 final release movement of the correcting mechanism causing said locking arm to be removed from the controlling mechanism whereby the driving mechanism may be again moved from driving relation with the 25 indicating mechanism.
31. In a calculating machine, the combination with indicating mechanism comprising a plurality of gear wheels, of driving gearing mechanism, escapement mechanism 30 associated with the indicating mechanism to cause bodily advancements thereof for successive engagement with the gear wheels of this driving mechanism, keys for the machine, actuating frames connected with the 35 keys, cam mechanism associated with said frames and driving gear mechanism and adapted upon actuation of a key to cause rotation of the driving gearing mechanism, controlling mechanism associated with the 40 driving gearing and with the actuating frames for controlling the meshing relation of the driving gear with the indicating mechanism, said driving gearing being normally held by the controlling mechanism 45 and prevented from meshing relation, locking mechanism associated with the actuating frames and with the indicating mechanism frame, actuation of a key causing first actuation of the locking mechanism to lock the 50 indicating mechanism against bodily advancements by the escapement mechanism, further actuation of a key then causing movement of the driving gearing mechanism into meshing relation with the indicating 55 mechanism, and final actuation of a key 60
- then causing rotation of the driving gearing mechanism and of the engaged indicating mechanism, locking means adapted upon insufficient actuation of a key to engage the actuating frame to prevent restoration of the key and of the parts associated therewith, correcting mechanism, a lever for the correcting mechanism adapted upon actuation to release the locking mechanism from the actuating frame, a locking lever associated with the correcting mechanism normally held by the lever thereof out of engagement with the controlling mechanism and adapted upon actuation of the lever to lock the controlling mechanism before actuation of the locking mechanism by the lever whereby the driving gearing is maintained in meshing relation with the engaged indicating mechanism, means associated with the gearing mechanism lever and adapted upon return movement of said lever for association with the driving gearing mechanism to return said driving mechanism toward its normal position before actuation thereof to influence the indicating mechanism, final return movement of the lever causing the locking arm to be released from the controlling mechanism to allow the driving gearing to be unmeshed from the indicating mechanism, and means after restoration of all the parts to their normal position for releasing the locking mechanism from the indicating mechanism frame to allow advancement of said frame by the escapement mechanism. 100
32. In a calculating machine, the combination with indicating mechanism, of driving mechanism therefor, keys for the machine, actuating frames connected with the keys and adapted for engagement with the driving mechanism, controlling mechanism associated with the driving mechanism and with the actuating frames for controlling the driving relation of the driving mechanism with the indicating mechanism, means tending to normally actuate the controlling mechanism to hold the driving mechanism from driving relation with the indicating mechanism, means upon actuation of a key for causing first movement of the controlling 105 mechanism to carry the driving mechanism into driving relation with the indicating mechanism and then to cause actuation of the driving mechanism and of the engaged indicating mechanism, and lever mechanism 110 adapted to move and to hold the controlling mechanism out of range of the cam frames whereby the keys may be actuated to cause actuation of the driving mechanism without causing actuation of indicating mechanism. 115
33. In a calculating machine, the combination with indicating mechanism, of driving mechanism therefor, controlling mechanism for controlling the driving relation of the driving mechanism with the indicating 120 mechanism
- 125
- 130

mechanism, said controlling mechanism being normally disposed to prevent driving relation of the driving and the indicating mechanism, keys for the machine, actuating frames connected with said keys and associated with the driving mechanism and with the controlling mechanism therefor, actuation of a key under normal conditions causing first actuation of the controlling mechanism to move the driving mechanism into driving relation and then to cause actuation of the driving mechanism and of the engaged indicating mechanism, and adjusting lever mechanism adapted upon actuation to move the controlling mechanism out of range of the actuating frames in a position to maintain the position of the driving mechanism out of driving relation with the indicating mechanism, whereby the keys and the driving mechanism may be actuated without causing actuations of indicating mechanism.

34. In a calculating machine, the combination with indicating mechanism, of driving mechanism therefor, controlling mechanism for controlling the driving relation of the driving mechanism with the indicating mechanism, keys for the machine, actuating frames secured to said keys and associated with the driving mechanism and with said controlling mechanism, detent mechanism normally in engagement with the driving mechanism to prevent actuation thereof independently of said keys, said controlling mechanism being normally disposed to hold the driving mechanism from driving relation with the indicating mechanism, and adjusting lever mechanism adapted upon actuation to withdraw the detent mechanism from the driving mechanism and to prevent actuation of the controlling mechanism by the actuating frame upon depression of a key whereby the keys and driving mechanism may be actuated without causing actuation of the indicating mechanism.

45. 35. In a calculating machine, the combination with indicating mechanism comprising a row of actuating gears, of a driving gear for association with the indicating gears, a shaft for the driving gear, a pivot shaft, an actuating arm for said pivot shaft, link and lever mechanism extending from said pivot shaft into engagement with the driving gear and normally disposed to hold said driving gear to prevent meshing thereof with the indicating mechanism, keys for the machine, an actuating frame for each key associated with the actuating arm of the pivot shaft and with actuating arms on the gear shaft, actuation of a key tending to cause first actuation of the pivot shaft and intervening mechanism to move the driving gear into meshing relation with the corresponding indicating gear and then to cause rotation of the driving gear and the engaged indicating gear, and adjusting lever mechanism adapt-

ed upon actuation to prevent engagement of the pivot shaft and actuating arm with the actuating frame whereby upon actuation of a key the driving gear will be rotated without causing rotation of the indicating mechanism.

36. In a calculating machine, the combination with indicating mechanism comprising a row of actuating gears, of a driving gear for association with the indicating gears, a shaft for the driving gear, a pivot shaft, an actuating arm for said pivot shaft, link and lever mechanism extending from said pivot shaft into engagement with the driving gear and normally disposed to hold said driving gear to prevent meshing thereof with the indicating mechanism, keys for the machine, an actuating frame for each key associated with the actuating arm of the pivot shaft and with actuating arms on the gear shaft, actuation of a key tending to cause first actuation of the pivot shaft and intervening mechanism to move the driving gear into meshing relation with the corresponding indicating gear and then to cause rotation of the driving gear and the engaged indicating gear, and an adjusting lever adapted upon actuation to rotate the pivot shaft to carry the actuating arm therefor out of the path of the actuating frame and to hold said pivot shaft and intervening mechanism to prevent meshing engagement of the driving gear whereby upon actuation of a key and the actuating frame connected therewith said driving gear may be rotated when out of meshing engagement whereby said indicating mechanism will not be influenced.

37. In a calculating machine, the combination with indicating mechanism comprising a row of actuating gears, of a driving gear for rotating said actuating gears, a pivot shaft, an actuating arm for said pivot shaft, link and lever mechanism between said pivot shaft and driving gear, keys for the machine, an actuating frame connected with each key and having a cam projection, the actuating arm for the pivot shaft being normally disposed before said projection and in such a position that the link and lever mechanism is in position to hold the driving gear to prevent meshing engagement thereof with the indicating gears, actuation of a key tending first to carry the cam projection to actuate the pivot shaft to move the driving gear into meshing relation with the corresponding indicating gear, and further actuation of the key causing then actuation of the cam mechanism engaged by the actuating frame to cause rotation of the driving gear and indicating gear connected therewith, a detent normally in association with the driving mechanism to prevent rotation of the driving gear independently of the keys, and an actuating lever for said detent mech-

anism disposed in the path of the actuating arm of the pivot shaft whereby actuation of a key and consequent actuation of the actuating arm causes disengagement of the detent to allow subsequent rotation of the driving gear.

38. In a calculating machine, the combination with indicating mechanism, of driving mechanism therefor, controlling mechanism for controlling the driving relation of the driving mechanism with the indicating mechanism and normally disposed to prevent driving relation, keys for the machine associated with the controlling mechanism and with the driving mechanism, actuation of a key tending normally to first actuate the controlling mechanism to move the driving gear into driving relation and then to cause actuation thereof and of the indicating mechanism engaged thereby, and means for preventing actuation of the controlling mechanism upon depression of a key whereby the driving mechanism may be actuated when out of driving relation where- 25 by the indicating mechanism will not be influenced.

39. In a calculating machine, the combination with indicating mechanism, of driving mechanism therefor, controlling mechanism for the driving mechanism normally disposed to hold the driving mechanism from driving relation with the indicating mechanism, keys for the machine associated with the driving mechanism and with the controlling mechanism therefor, locking means normally associated with the driving mechanism to prevent actuation thereof independently of the keys, actuation of a key tending normally to first actuate the controlling mechanism to move the driving mechanism into driving relation then to cause actuation of the locking means to release the driving mechanism and then to cause actuation of the driving mechanism and of the engaged indicating mechanism.

40. In a calculating machine, the combination with indicating mechanism, of driving mechanism therefor, controlling mechanism for the driving mechanism normally disposed to hold the driving mechanism from driving relation with the indicating mechanism, keys for the machine associated with the driving mechanism and with the controlling mechanism therefor, locking means normally associated with the driving mechanism to prevent actuation thereof independently of the keys, actuation of a key tending normally to first actuate the controlling mechanism to move the driving mechanism into driving relation then to cause actuation of the locking means to release the driving mechanism and then to cause actuation of the driving mechanism and of the engaged indicating mechanism, and adjusting lever mechanism adapted

upon actuation to withdraw the controlling mechanism from the influence of the keys and to release the locking mechanism whereby a key may be actuated to actuate the driving mechanism without causing actuation of the corresponding indicating mechanism.

41. In a calculating machine, the combination with a driving gear, of a plurality of totalizer gears mounted in a row and adapted to travel to be successively engaged by the driving gear, carryover mechanism associated with the totalizer gears, locking means normally in engagement with the carryover mechanism to prevent actuation thereof, driving means for causing rotation of the driving gear when in engagement with a totalizer gear, and releasing means adapted upon actuation of the driving means to release the locking means to allow rotation of the engaged totalizer wheel by the driving wheel.

42. In a calculating machine, the combination with a driving gear, of driving mechanism therefor, a plurality of totalizer gears mounted in a row and adapted to travel into successive engagement with the driving gear, carryover and locking mechanism associated with each totalizer gear and having a carryover pinion composed of two relatively movable sections, locking means for locking one of said sections with respect to the corresponding totalizer gear, the other section being in mesh with an adjacent totalizer gear, and a locking pinion engaging both sections.

43. In a calculating machine, the combination with a driving gear, of driving mechanism therefor, a plurality of totalizer gears mounted in a row and adapted to travel into successive engagement with the driving gear, carryover and locking mechanism associated with each totalizer gear and having a carryover pinion composed of two relatively movable sections, locking means for locking one of said sections with respect to the corresponding totalizer gear, the other section being in mesh with an adjacent totalizer gear, a locking pinion engaging both sections, whereby the adjacent totalizer gear is normally locked against direct rotation, and means upon rotation of the other totalizer gear for releasing the locking mechanism associated therewith whereby the normally rigid section is rotated and said rotation transmitted through the locking pinion to the other section and rotation thereby caused of the adjacent totalizer gear engaged by said other section.

44. In a calculating machine, the combination with a driving wheel, of driving mechanism therefor, a plurality of totalizer gears mounted in a horizontal row and adapted to travel and successively engage with the driving gear, a carryover gear plate and a locking

cam secured to each totalizer gear wheel, sets of coöperating carryover locking mechanisms pivoted on a shaft, each set comprising a pinion gear for meshing with the carryover gear plate, a locking wheel for engaging with the locking cam, carryover pinion mechanism composed of two similar sections, one of said sections being secured to the locking wheel and pinion plate and the other section being in mesh with the adjacent totalizer gear, a locking pinion engaging both said sections whereby the adjacent totalizer gear is locked against direct actuation while the locking cam and wheel of the other totalizer gear are in locking engagement, and means at a certain position of the one totalizer gear for causing release of the locking mechanism to allow rotation of the locking wheel and the pinion plate and carryover section connected therewith, said rotation being transmitted from one section through the locking pinion and to the other section in mesh with the adjacent totalizer gear whereby said adjacent gear is also rotated.

45. In a calculating machine, the combination with a totalizer frame adapted to travel horizontally, of a stationary driving wheel, driving mechanism for said driving wheel, a plurality of totalizer gears arranged in a row and adapted to mesh with the driving gear as the totalizer frame travels, carryover and locking mechanism secured to each totalizer gear, shafts for supporting carryover and locking mechanism associated with the locking mechanism on the totalizer gears, locking pinions normally in engagement with the carryover mechanism to prevent actuation of the totalizer gear engaged by the driving gear, and means upon actuation of the driving mechanism for releasing the locking pinion to allow subsequent rotation of the totalizer gear by the driving gear in engagement therewith.

46. In a calculating machine, the combination with a main driving wheel pivoted to the machine frame, of driving mechanism therefor, a plurality of totalizer gears mounted in a horizontal row and adapted to travel to be successively engaged by the driving gear, a carryover gear plate and locking cam secured to each totalizer gear, sets of associated carryover and locking mechanism pivoted on a shaft, each set comprising a pinion plate for engaging with the gear plate, a locking wheel for engaging with the locking cam, and carryover pinion mechanism composed of two similar sections, one of said sections being secured to the locking wheel and pinion plate, the other section being relatively movable and in mesh with the adjacent totalizer gear, the pinion plate, locking wheel and associated section being normally locked against rotation, and a locking pinion in mesh with both said sections whereby said

adjacent totalizer gear is normally locked 65 against direct actuation, rotation of the corresponding set, however, at a certain position of the associated totalizer gear causing rotation of the adjacent totalizer gear through said sections and engaging locking 70 pinion.

47. In a calculating machine, the combination with a driving gear, of driving mechanism therefor, a totalizer comprising a plurality of totalizer gears arranged in a horizontal row and adapted to travel to carry 75 said gears successively into engagement with the driving gear, carryover and locking mechanism associated with adjacent totalizer gears, carryover pinion mechanism for said 80 carryover and locking mechanism, and a locking pinion engaging the carryover pinion mechanism, said locking pinion serving as a clutch to transmit actuations of one totalizer gear to the adjacent totalizer gear but acting 85 as a lock to prevent direct actuation of the adjacent totalizer gear.

48. In a calculating machine, the combination with a driving gear, of driving mechanism therefor, a totalizer comprising a plurality of totalizer gears arranged in a horizontal row and adapted to travel to carry 90 said gears successively into engagement with the driving gear, carryover and locking mechanism associated with adjacent totalizer gears, 95 carryover pinion mechanism for said carryover and locking mechanism, a locking pinion engaging the carryover pinion mechanism, said locking pinion serving as a clutch to transmit actuations of one totalizer gear 100 to the adjacent totalizer gear but acting as a lock to prevent direct actuation of the adjacent totalizer gear, and means actuated upon actuation of the driving mechanism for releasing the locking pinion from the carryover 105 pinion mechanism whereby a totalizer gear may be directly actuated.

49. In a calculating machine, the combination with a driving gear, of driving mechanism therefor, a plurality of totalizer gears 110 mounted in a row and adapted to travel into successive engagement with the driving gear, carryover and locking mechanism associated with each totalizer gear and having a carryover pinion composed of two relatively 115 movable sections, and locking means for locking one of said sections with respect to the corresponding totalizer gear, the other section being in mesh with an adjacent totalizer gear, said sections being normally locked 120 together.

50. In a calculating machine, the combination with indicating mechanism adapted to travel, of driving mechanism therefor, keys for actuating the driving mechanism 125 and thereby the indicating mechanism, an arm actuated upon depression of a key, and abutments in suitable places for said arm

whereby the actuation of keys will be prevented at certain positions of the indicating mechanism during its travel.

51. In a calculating machine, the combination with totalizer mechanism comprising a plurality of totalizer gears mounted in a horizontal row and divided into groups, of driving mechanism associated with keys of the machine, a driving gear for the driving mechanism, said totalizer gears and driving wheel being relatively movable whereby said gear may successively engage the totalizer gears, an arm moved upon actuation of a key, and an abutment suitably disposed to prevent actuation of the arm to prevent actuation of the key when said driving wheel is in position between groups of the totalizer gears.

52. In a calculating machine, the combination with totalizer mechanism comprising a plurality of totalizer gears mounted in a horizontal row, of driving mechanism connected with keys of the machine, a driving gear for the driving mechanism, and escapement mechanism for causing relative movements between the totalizer gears and the driving gear whereby said driving gear may engage successively with the totalizer gears, the spacing between totalizer gears being greater than the spacing of the escapement mechanism.

53. In a calculating machine, the combination with totalizer mechanism comprising a plurality of totalizer gears mounted in a horizontal row, of a driving gear associated with keys of the machine, and escapement mechanism associated with the keys for causing relative bodily movement between the totalizer gears and the driving gear, actuation of a key causing first rotation of the driving wheel and the totalizer gear driven thereby and then actuation of the escapement mechanism to cause relative movement so that the driving gear is in driving relation with the next totalizer gear, the spacing between totalizer gears being greater than the relative distance of travel between the totalizer gears and driving wheel by the escapement mechanism, the meshing width of the driving gear being greater than that of the totalizer gears.

54. In calculating mechanism adapted for attachment to a typewriting machine, the combination with totalizer mechanism connected with the escapement carriage of the machine to travel therewith, of a plurality of totalizer gears for the totalizer mechanism mounted in a horizontal row, a driving gear associated with the keys of the machine, actuation of a key causing first rotation of the driving gear and of the totalizer gear in mesh therewith and then actuation of the escapement mechanism to move the totalizer mechanism to carry the next totalizer gear into

meshing relation with the driving gear, the spacing distance between totalizer gears being greater than the spacing advancements due to the escapement mechanism and the driving gear having sufficiently greater meshing width than the totalizer gears to insure proper meshing relations as the totalizer gears successively mesh with the driving gear.

55. The combination with a totalizer, of a driving gear, an escapement for causing relative movements between the totalizer and the driving gear whereby said gear may engage with the totalizer gears, the spacing between the totalizer gears being different from the spacing of the escapement.

56. The combination with a totalizer, of a driving gear, an escapement for causing relative movements between the totalizer and the driving gear whereby said gear may engage with the totalizer gears, the spacing between totalizer gears being greater than the spacing of the escapement.

57. The combination with a totalizer, of a driving gear, an escapement for causing relative movements between the totalizer and the driving gear whereby said gear may engage with the totalizer gears, the spacing between the totalizer gears being different from the spacing of the escapement, a scale carried on the totalizer frame and marked in accordance with the positions of the totalizer gears, and a pointer for indicating on the scale the particular totalizer gear engaged at any time by the driving gear.

58. The combination with a totalizer, of a driving gear, an escapement for causing relative movements between the totalizer and the driving gear whereby said gear may engage with the totalizer gears, the spacing between totalizer gears being greater than the spacing of the escapement, a scale carried on the totalizer frame and marked in accordance with the positions of the totalizer gears, and a pointer for indicating on the scale the particular totalizer gear engaged at any time by the driving gear.

59. The combination with a totalizer adapted to travel with the escapement of a machine, of a stationary driving gear for engaging the totalizer gears, the spacing between the totalizer gears being different from the spacing of the escapement, a scale carried by the totalizer frame and provided with marks representing the totalizer gear wheels, and a stationary pointer for association with the scale to indicate thereon which particular totalizer gear is being actuated by the driving gear.

60. The combination with a totalizer adapted to travel with the escapement of a machine, of a stationary driving gear for engaging the totalizer gears, the spacing between the totalizer gears being different from the spacing of the escapement, a scale

carried by the totalizer frame having indicating marks whose spacing is equal to the escapement spacing, said marks representing the totalizer gears wheels, and a stationary 5 pointer for indicating on the scale the particular totalizer gear wheel engaged by the driving gear.

61. In a calculating machine, keys, a totalizer, a segmental gear for operating said totalizer, a shaft whereto said segmental gear is secured, a series of angularly displaced arms extending from said shaft, a series of key operated cams each adapted to engage one of said arms for operating them, 10 and an extension upon each of said cams adapted when starting from normal position to strike its coöperating arm when the latter is out of normal position, whereby a second key is prevented from being depressed until 15 the prior key has permitted said shaft to return to normal position.

62. In a calculating machine, a totalizer, differential mechanism for operating the same, said differential mechanism including 25 an actuating cam for producing rotation of the totalizer gears, a controlling cam for controlling the connections between the differential mechanism and the totalizer said cams being pivoted about a common axis, the controlling cam requiring a definite angular movement for proper operation of the parts, 30 a lost motion connection between said cams whereby the angular throw of the actuating cam is less than the angular throw of the controlling cam, and keys for operating said controlling cam.

63. In a calculating machine, a totalizer, differential mechanism for operating the same, said differential mechanism including 40 an actuating cam for producing rotation of the totalizer gears, a controlling cam for controlling the connections between the differential mechanism and the totalizer, said cams being pivoted about a common axis, the controlling cam requiring a definite angular movement for proper operation of the parts, 45 one of said cams having a slot and the other a post extending into said slot to make lost motion connection between said cams, and keys 50 for operating said controlling cams.

64. In a calculating machine totalizer, a series of carryover mechanisms, intermediate locking pinions for uniting the carryover mechanisms adjacent to each other, each of 55 said locking pinions being mounted on a lever to connect and to disconnect said carryover mechanisms, and movable means continuously in contact with the intermediate locking pinions for holding said locking pinion 60 while out of engagement with its coöperating carryover mechanism.

65. In a calculating machine totalizer, the combination with carrying gears, carrying pinions and auxiliary locking pinions bodily 65 movable toward and from said carrying pin-

ions for connecting them in pairs and disconnecting them, pivoted levers arranged side by side for moving said locking pinions bodily, and movable holding means common to a plurality of said levers and auxiliary locking 70 pinions, said holding means remaining continuously in contact with the locking pinion when the latter is away from its coöperating carrying pinions for preventing accidental rotation of said locking pinion. 75

66. In a calculating machine totalizer, the combination of carrying gears, carrying pinions and auxiliary locking pinions bodily movable toward and from said carrying pinions for connecting them in pairs and disconnecting them, pivoted levers arranged side by side for moving said locking pinions bodily, a movable bar common to a plurality of said levers and locking pinions and continuously in contact with the auxiliary 80 pinions when the latter are away from their coöperating carrying pinions, and a spring to keep said bar in contact with said locking pinions, for preventing accidental rotation of 85 said locking pinion. 90

67. In a calculating machine, a totalizer, differential mechanism for operating the totalizer, and keys for operating the differential mechanism, said differential mechanism including a reciprocatable member which is 95 key driven to move in one direction on the down stroke of a key and spring urged to return to normal position upon the up stroke of the key, a stop for limiting the return movement of said reciprocatable member, and means for preventing the rebound of 100 said reciprocatable member in consequence of the forcible striking thereof against said stop. 105

68. In a calculating machine, a totalizer, differential mechanism for operating the totalizer, and keys for operating the differential mechanism, said differential mechanism including a reciprocatable member which is 110 key driven to move in one direction on the down stroke of a key and spring urged to return to normal position upon the up stroke of the key, a stop for limiting the return movement of said reciprocatable member, and means for preventing the rebound of 115 said reciprocatable member in consequence of the forcible striking thereof against said stop, 120 said preventing means consisting of a spring urged detent adapted to engage a shoulder upon said reciprocatable member as the latter contacts said stop. 125

69. In a calculating machine, a totalizer, differential mechanism for operating the totalizer, and keys for operating the differential mechanism, said differential mechanism including a reciprocatable member which is 125 key driven to move in one direction on the down stroke of a key and spring urged to return to normal position upon the up stroke of the key, a stop for limiting the return 130

movement of said reciprocatable member, means for preventing the rebound of said reciprocatable member in consequence of the forcible striking thereof against said stop, 5 said preventing means consisting of a spring urged detent adapted to engage a shoulder upon said reciprocatable member as the latter contacts said stop, and releasing mechanism operative during the initial portion of 10 the down stroke of the key for withdrawing

said detent from said shoulder to thereby permit the succeeding movements of said reciprocatable member.

In testimony whereof, I hereunto subscribe my name this 20th day of October, 15 A. D. 1907.

JOHN C. WAHL.
